PAGE 4

FIG.4

FIG. 5

FIGURE 1 is a front perspective view of a combined printing machine and control cabinet, embodying my new design;

FIGURE 2 is a left side elevational view thereof;

FIGURE 3 is a right side elevational view thereof;

FIGURE 4 is a rear elevational view thereof; and

FIGURE 5 is a top plan view thereof.

I claim:

The ornamental design for a combined printing machine and control cabinet, substantially as shown.
